UNITED STATES PATENT OFFICE

2,453,538

CONSTANT PRESSURE PUMP

William T. Rauch, Voorheesville, N. Y., assignor
to General Electric Company, a corporation of
New York

Application October 4, 1947, Serial No. 778,010

11 Claims. (Cl. 103—161)

1

The present invention relates to radial piston pumps and more particularly to pressure governing apparatus for such pumps.

In the prior art some attempts have been made to provide pressure governing apparatus for radial piston type pumps. Since variable stroking means such as a movable stroking ring may be readily provided in this type of pump, these previous attempts have taken the form of governing apparatus for the stroking ring. However, one of the inherent difficulties with this type of pump is that the reaction force of the fluid being pumped tends to restore the stroking ring toward neutral, or low stroke, position. Accordingly, it is necessary to hold the stroking means positively against this reaction force as well as to control its movement to govern the pressure supplied by the pump. While some attempts have been made to control the discharge pressure of the pump by varying the position of the stroking ring, these efforts have produced governing apparatus with undesirable regulation since the discharge pressure decreases with an increased load on the system. With this type of apparatus, for each position of the stroking ring there is a predetermined pressure and flow condition in the system supplied by the pump.

It is an object of my invention to provide apparatus for automatically governing the fluid discharge pressure of a radial piston type pump independently of the flow requirements of the fluid system being supplied by the pump and the position of the stroking means.

A further object of my invention is to provide pressure governing apparatus for a radial piston pump which will maintain constant the pressure differential between the inlet and discharge lines of the pump.

A still further object of my invention is to provide governing apparatus to maintain stable and reliable operation of a radial piston pump at a constant differential between some low pressure, such as the inlet line pressure and the discharge line pressure.

Another object of my invention is to provide simple and inexpensive governing apparatus for a radial piston pump.

Further objects and advantages of my invention will become apparent and my invention will be better understood from the following description referring to the accompanying drawing, and the features of novelty which characterize my invention will be pointed out with particularity in the claims annexed to and forming a part of this specification.

2

In the drawings,

Fig. 1 is a sectional view of a radial piston pump embodying pressure governing apparatus in accordance with my invention.

Fig. 2 is a cross-sectional view looking in the direction of the arrows 2—2 in Fig. 1 with a portion of the pump block cut away to show part of the pressure governing apparatus.

Referring to the drawing I have shown in Fig. 10 a radial piston pump having a back flange 1 with a pintle 2 located in an axial bore 3 in the center of the flange. Pintle 2 is so arranged that it separates inlet and discharge means, such as bores 4 and 5, respectively, in the flange which radially intersect bore 3. To pump fluid from the inlet side of the pintle to the discharge side I provide a rotatable cylinder 6 including bearing surface 7 mounted on extension 8 of the flange 1 surrounding pintle 2. Piston means, such as 20 balls 9, are reciprocably mounted in a plurality of radial bores 10 which serve as cylinders in block 6. Back flange 1 is provided with an axial bore 11 parallel to bore 3 for supplying makeup fluid from the sump (not shown) to the fluid system in which the pump is connected. An annular groove 12 also located in the back flange connects with bore 11. Pump block 6 is provided with a plurality of radial veins 13 adjacent the annular groove 12 and these veins serve as a centrifugal pump to increase the pressure of the fluid entering the pump through bore 11 and annular groove 12. Veins 13 pump the fluid into annular groove 14 which is in communication with inlet bore 4 through passage 15.

Driving means for the pump elements, block 6 and balls 9, is provided through shaft 16 adapted to be rotated by an external power source (not shown). Shaft 16 rotates an Oldham coupling 17 through key 18 in a keyway in shaft 16. Oldham coupling 17 comprises a driving flange 19, an intermediate flange 20, and a pair of shoulders 21 integrally formed on the cylinder block 6. Any slight misalignment of shaft 16 and cylinder block 6 may be compensated for by means of Oldham coupling 17.

A stroking means such as annular ring 22 is provided to vary the work stroke of the pump by controlling the stroke of balls 9 within cylinders 10. As shown ring 22 surrounds the cylinder block 6 to maintain balls 9 in the cylinder bores 10 and provide a raceway for the balls. A housing member 23 having an ovate recess 24 adapted to surround ring 22 mates with flange 1 to enclose the radial pump and stroking means. A fluid seal 25 to prevent leakage of fluid under

pressure is provided between the Oldham coupling 17 and the housing 23.

As indicated above the stroking ring 22 may be moved radially with respect to the axis of the cylinder block 6, but housing 23 is provided with a pair of inserts 26 to limit this motion to movement parallel to the major axis of pintle 2. Ovate recess 24 is so located that movement of ring 22 in one direction (downwardly in Fig. 2) reduces the pump stroke, while movement in the opposite direction increases the stroke.

In order to move the stroking ring 22 to vary the stroke of balls 9, a pair of pistons 27 and 28 are reciprocably mounted in opposing bores 29 and 30 adjacent recess 24 in housing 23. As shown in the drawing, end 31 of piston 28 is adapted to move inwardly against stroking ring 22 to hold pump block 6 in full stroke position. However, end 32 of piston 27 is also adapted to move inwardly against the stroking ring to actuate the block toward neutral, or low stroke, position.

In order to move the stroking ring toward full stroke position initially, biasing means are provided to urge piston 28 inwardly. As shown, spring means, such as coil spring 33, is located between threaded plug 34 and end 28' of piston 28 to urge the piston inwardly. In addition to spring 33, I provide fluid pressure means to assist the biasing force of the spring. Fluid pressure in discharge means 5 is introduced to cylinder 30 through bore 35 in casing 1 and passage 36 in housing 23. In this way piston 28 and stroking ring 22 are maintained in full stroke position against the reaction force developed by piston balls 9 acting against stroking ring 22. Thus, ring 22 is held in full stroke position against the reaction force which tends to restore the ring to neutral position when the pistons are pumping fluid under pressure.

To overcome the biasing force applied to ring 22 through piston 28, counterbiasing means are provided to urge end 32 of piston 27 against the ring. This counterbiasing means is selectively supplied by the fluid pressure in either inlet means 4 or discharge means 5. To control the selection of the fluid pressure to be introduced into cylinder 29 I have provided pressure actuated valve means located in bore 37 in flange 1. Passage 38 provides fluid conduit means between cylinder 29 and valve port 39 in bore 37. Passages 40 and 41 respectively communicate with fluid inlet means 4 and fluid discharge means 5 and a two land piston-type valve 42 is arranged to selectively connect either passage 40 or passage 41 to valve port 39 and thus to cylinder 29. In order to initially position valve 42 so that piston 27 is connected to the fluid inlet pressure I provide valve biasing means comprising coil spring 43, seat 44, and threaded adjusting plug 45 to hold valve 42 in the extreme right-hand position (with respect to Fig. 2) to maintain communication between cylinder 29 and inlet means 4 through passage 40 and bore 37. In addition to the valve biasing means the fluid inlet pressure operates against valve 42 and seat 44 to assist spring 43 in maintaining the valve in this position. Valve 42 is so arranged that when the fluid pressure in discharge means 5 increases, the pressure operates against shoulder 46 and end 47 of the valve 42 to move the valve against the force of coil spring 43 and the inlet fluid pressure acting on valve 42. A passage 48 in valve 42 is provided to admit fluid into chamber 50 formed by sealing plug 51 and end 47 of the valve 42 to permit the

fluid pressure to operate against end 47. In this manner the fluid pressure in discharge means 5 actuates valve 42 against the valve biasing means and the inlet fluid pressure and opens cylinder 29 to the discharge fluid pressure through port 39 and passage 38. The land of valve 42 adjacent end 47 is provided to insure proper alignment of valve 42 with respect to port 39.

Operation of my pressure governing apparatus is as follows: Before the pump is started coil spring 33 biases piston 28 to thereby position stroking ring 22 in full stroke position relative to cylinder block 6. For clockwise rotation of the cylinder block (as shown in Fig. 2) ring 22 is held in a raised position for full stroke operation of the pump. When the cylinder block 6 is rotated by the external power source through shaft 16 and Oldham coupling 17, the ball pistons 9 are forced outwardly by centrifugal force during rotation of the cylinder block 6 through one half revolution about pintle 2 (left-hand side of Fig. 2) and are fully extended in the top-most position in Fig. 2. As the block is rotated through the right-hand portion of the revolution, the piston balls are forced inwardly by stroking ring 22 and cause the fluid entrapped between balls 9 and cylinders 10 to be forced into the right-hand portion of pintle 2 and thus into discharge means 5. The fluid pressure developed in discharge means 5 is applied to piston 28 through passages 35 and 36 to assist spring 33 in holding piston 28 in the extended position to thereby hold stroking ring 22 in full stroke position against the fluid reaction force of the fluid being pumped in cylinders 10. At the same time cylinder 29 is connected to inlet means 4 through passage 40, bore 37, valve port 39, and passage 38. It will be noted that piston means 27 and 28 are arranged to hydraulically lock the stroking ring 22 in any desired position to govern the work stroke of the pump in accordance with the differential pressure across inlet means 4 and discharge means 5, independently of the fluid reaction force developed by ball pistons 9 acting against ring 22. So long as the flow in the system being supplied by the pump is sufficiently high the stroking ring will be maintained in full stroke position. However, if the flow is decreased with the pump operating at the same speed, the pressure in discharge means 5 will increase. This increased pressure is applied to valve 42 through passage 41 and will operate against shoulder 46 and end 47 of valve 42 to overcome the force of coil spring 43 and the inlet pressure acting on valve 42 to thereby move valve 42 toward the left until passage 38 and cylinder 29 are opened to the higher fluid pressure in discharge means 5. Since piston 27 is larger than piston 28 the counterbiasing force on piston 27 will overcome the biasing force of piston 28 and move the stroking ring 22 toward neutral or low stroke position. However, piston 27 will only be moved far enough to reduce the stroke of the pump to such a position that the pressure differential across inlet means 4 and discharge means 5 will be restored to a pre-set pressure differential across the pump. This pressure differential may be determined by the adjustment of threaded plug 45 which initially positions coil spring 43 to hold valve 42 against the pressure force in discharge means 5. In this manner the pressure differential across inlet means 4 and discharge means 5 may be set and held constant by movement of the stroking ring 22 to reduce the flow when the differential pressure increases and to increase the flow when the differential pressure decreases.

By the arrangement of piston valve 42 acting against coil spring 43 and the low pressure for moving stroking ring 22 by piston 27, the movement of the stroking ring is made pressure sensitive and independent of the flow condition in the system supplied by the pump except insofar as the flow varies the pressure in the discharge means. In this way, a floating type of control is obtained wherein the same differential pressure may be maintained for any flow demand on the system, since there is no fixed relationship between stroking ring position and the discharge pressure of the pump. This reduces undesirable regulation and maintains the pressure constant irrespective of the flow demand on the pump. It will thus be apparent that the same pressure may be maintained at any position of the stroking ring since the stroking ring position will vary only with a change in differential pressure across the pump. By making piston 27 larger than piston 28, the force on ring 22 due to piston 28 is readily overcome by the counterbiasing force on piston 27. Since the pressure responsive element is remote from piston 27, the piston may move through its complete range of travel for a small displacement of the valve against the spring and thereby reduce to a minimum the spring gradient effect of displacing the valve by pressure against a coil spring. In this way the governing apparatus operation is both stable and reliable.

While I have shown the preferred embodiment of my invention it will be apparent to those skilled in the art that the piston means may be arranged to reciprocate in a single cylinder with the piston connected to the stroking ring to positively move the ring in response to fluid pressure admitted to the opposite ends of the cylinder.

It will also be apparent that the pressure maintained by the pump may be the pressure differential between the pressure in the discharge means and any low pressure connected to the low pressure side of the valve means, such as atmospheric pressure, since the movement of the stroking ring is substantially due to the pressure differential appearing across the piston valve 42.

While I have illustrated and described a particular embodiment of my invention, modifications thereof will occur to those skilled in the art. I desire it to be understood, therefore, that my invention is not to be limited to the particular arrangement disclosed, and I intend in the appended claims to cover all modifications which do not depart from the spirit and scope of my invention.

What I claim as new and desire to secure by Letters Patent of the United States is:

1. In combination, a casing, a radial piston pump block rotatable in said casing, a stroking ring for varying the work stroke of said pump, fluid inlet means and fluid discharge means for said pump, a pair of hydraulic pistons connected to position said ring, means for subjecting one of said pistons to the pump discharge pressure, means including a valve member for selectively subjecting the other of said hydraulic pistons to either the pump inlet or said discharge pressure and means for positioning said valve member in accordance with the difference in said pump inlet and discharge pressures.

2. Pressure governing apparatus for a radial piston pump having a variable stroking means, said apparatus comprising a pair of hydraulic pistons in opposed relation adapted to move said stroking means, conduit means for subjecting one of said pistons to the discharge pressure of said

pump, and means for selectively subjecting the other of said pistons to either the inlet pressure or said discharge pressure of said pump, said means including a valve operable in response to the difference in said pump inlet and discharge pressures.

3. In combination, a casing, a radial piston pump rotatable in said casing, a stroking ring for varying the stroke of said pump, fluid inlet means and fluid outlet means for said pump, biasing means for maintaining said ring in full stroke position initially, means for reducing said stroke of said pump to maintain the fluid pressure differential between said outlet means and said inlet means constant, said means comprising piston means adapted to move said stroking ring, said piston means being reciprocable in a chamber in said casing adjacent said stroking ring and movable in response to fluid pressure in said chamber, pressure actuated valve means for selectively connecting said chamber with either said outlet means or said inlet means, said valve means including biasing means for maintaining said chamber in communication with said inlet means until the force due to said fluid pressure in said outlet means exceeds the force of said biasing means, said fluid pressure force adapted to actuate said valve means and connect said chamber with said outlet means whereby said piston means may move said stroking ring toward low stroke position to maintain said pressure differential between said outlet means and said inlet means constant.

4. In combination, a pump casing provided with fluid conduit means for admitting and discharging fluid, a radial piston pump rotatable in said casing, a stroking ring for varying the stroke of said pump between full stroke and low stroke positions, biasing means for maintaining said pump ring initially in said full stroke position, said biasing means comprising a piston adapted to reciprocate in a cylinder in said casing and to move said ring in response to fluid pressure in said cylinder, and fluid conduit means interconnecting said cylinder and the fluid discharge conduit of said pump whereby the pressure in said discharge conduit biases said ring to full stroke position, and counterbiasing means for moving said ring toward said low stroke position, said counterbiasing means comprising second piston means adapted to reciprocate in another cylinder in said casing and to move said ring in response to fluid pressure in said other cylinder, means including a valve for selectively interconnecting said cylinder with either said fluid discharge conduit or the fluid inlet conduit of said pump, valve biasing means for positioning said valve to connect said other cylinder and said inlet conduit initially, and means for then operating said valve in opposition to said biasing means in response to the pressure in said fluid outlet conduit whereby said second piston moves said stroking ring toward low stroke position to hold the pressure differential between said outlet conduit means and said inlet conduit means constant.

5. Pressure governing apparatus for a radial piston pump having movable stroking means for varying the work stroke of said pump, said apparatus comprising piston means reciprocably mounted in cylinder means and adapted to move said stroking means from full to neutral stroke, means for biasing said piston means to full stroke position initially, said means comprising fluid conduit means between the discharge means of

said pump and said cylinder means to admit fluid under pressure from said discharge means to bias said piston means, means for counterbiasing said piston means to neutral stroke position, said counterbiasing means comprising pressure actuated valve means for connecting said cylinder means to said pump discharge means, valve biasing means to maintain said valve means closed to said discharge means until the force due to said pressure in said discharge means exceeds the force of said valve biasing means, and means for moving said valve means against said valve biasing means whereby said counterbiasing means operates said piston means against said biasing means to move said stroking means toward neutral position and maintain said discharge pressure constant irrespective of the fluid flow demand on the system supplied by said pump.

6. Pressure governing apparatus for a radial piston pump, said pump having a stroking ring for varying the work stroke of said pump from full stroke to low stroke position, said apparatus comprising piston means for biasing said ring into said full stroke position initially, said piston means operated in response to fluid pressure in the discharge means of said pump, second piston means for counterbiasing said stroking ring toward low stroke position, pressure operated valve means for selectively operating said second piston means in response to either said discharge pressure or the pressure in the inlet means of said pump, and biasing means for said valve means to maintain said piston responsive to said inlet pressure until the force due to said discharge pressure exceeds the force of said valve biasing means, said valve being operated by said discharge pressure to subject said second piston means to said discharge pressure thereby moving said stroking ring toward low stroke position and reducing said work stroke whereby said discharge pressure is reduced to maintain constant the pressure differential between said inlet side and said outlet side of said pump.

7. Pressure governing apparatus for a radial piston pump having a stroking ring for varying said stroke, means for biasing said stroking ring into full stroke position initially comprising piston means reciprocable in cylinder means and fluid conduit means between the discharge means of said pump and said cylinder means for moving said piston means and said stroking ring to full stroke position in response to the pressure in said discharge means and means for counterbiasing said stroking ring toward low stroke position comprising second piston means reciprocable in said cylinder means, control valve means for selectively connecting said second cylinder means to either the inlet means of said pump or said discharge means, valve biasing means for maintaining said second cylinder means in communication with said inlet line initially, and means for moving said valve against said valve biasing means in response to an increase in differential pressure between said discharge means and said inlet means, said means moving said valve to connect said second cylinder means to said discharge means whereby said second piston means and said stroking ring may be moved toward low stroke position in response to said increase in said differential pressure to maintain constant said differential pressure.

8. A constant pressure pump comprising a casting having conduit means for admitting and discharging fluid, a radial piston pump rotatably

mounted within said casing and connected to said conduit means, a movable stroking ring for varying the work stroke of said pump between full and neutral stroke positions, a floating type of control means for moving said ring whereby said ring may be moved in response to changes in the differential pressure between said discharge means and the inlet means to maintain said differential pressure constant for any position of said ring, said means comprising a pair of pistons adapted to move said ring between said full and neutral stroke positions, said pistons being reciprocable in first and second cylinders in said casing to cause said ring movement, fluid connecting means between said first cylinder and said discharge means whereby one of said pistons is biased by said discharge pressure to hold said ring in said full stroke position initially, valve means for selectively connecting said second cylinder with either said inlet means or said discharge means, and valve biasing means for maintaining said second cylinder open to said inlet means until said differential pressure increased and the force due to the pressure in said discharge means exceeds the force of said biasing means, said valve means then being operated by said differential pressure to connect said second cylinder to said discharge means whereby the other of said pistons may be counterbiased by said discharge pressure to move said stroking ring toward said neutral position and thereby reduce said discharge pressure to maintain said differential pressure constant irrespective of the flow produced by said pump.

9. In a radial ball piston pump having a stroking ring for varying the work stroke of said pump, pressure actuated means for moving said stroking ring to full stroke position initially, said means comprising a cylinder, a piston reciprocable in said cylinder and adapted to move said stroking ring, and fluid conduit means between said cylinder and the discharge means of said pump whereby the discharge pressure is applied to said piston, and differential pressure means for moving said ring toward low stroke position to maintain the differential pressure across said pump constant, said means comprising a second cylinder having a piston reciprocable therein, said piston adapted to move said ring toward said low stroke position against the force of said pressure actuated means holding said ring in full stroke position, pressure responsive valve means for selectively connecting said second cylinder to either the inlet means of said pump or said discharge means, spring biasing means for positioning said valve means to subject said second cylinder to the pressure in said inlet means and holding said valve means until the force due to the differential pressure across said inlet means and said discharge means exceeds the pre-set condition of said biasing means, said valve means being adapted to move against said spring biasing means in response to said increase in differential pressure to connect said second cylinder to said discharge means whereby said second piston moves said ring to reduce said work stroke and said discharge pressure to maintain said differential pressure constant.

10. Pressure governing apparatus for a radial piston pump including a stroking ring for varying the stroke of the pistons of said pump from full to low stroke positions, fluid inlet means and fluid discharge means for said pump, said apparatus comprising a pair of cylinder means having pistons movable in said cylinders and adapted

to move said ring between said full and low stroke positions, pressure operable valve means adapted to selectively connect one of said cylinders to either said inlet means or said discharge means in response to the differential pressure across said valve, conduit means between said valve and said inlet and discharge means, spring biasing means for holding said valve in position to maintain said one cylinder open to said inlet means until the force due to said differential pressure exceeds the force of said spring biasing means, and fluid conduit means between the other of said cylinders and said discharge means so that said other cylinder is opened to the fluid pressure in said discharge means whereby said ring is biased to full stroke position initially and moved in response to an increase in differential pressure between said inlet means and said discharge means to a lower stroke position to maintain said differential pressure constant.

11. Pressure governing apparatus for a radial piston pump, said pump having stroking means for varying the work stroke of said pump between full stroke and low stroke position, said apparatus comprising pressure responsive means for biasing said stroking means to said full stroke position initially, said means including cylinder means, piston means movable in said cylinder means and adapted to move said stroking means, and conduit means between said cylinder means and the discharge means of said pump whereby the fluid pressure in said discharge means actuates said piston means and stroking means to said full stroke position, and differential pressure re-

sponsive means for counterbiasing said stroking means toward said low stroke position when the differential pressure across said pump exceeds a pre-set condition, said means comprising second cylinder means, second piston means movable in said second cylinder means for moving said stroking means against said pressure responsive means, a valve for selectively connecting said second cylinder means to either the inlet means for said pump or said discharge means, adjustable valve biasing means for assisting the pressure in said inlet means in maintaining said valve in position to connect said second cylinder means to said inlet means initially, and adjusting means for pre-setting said valve biasing means, said valve being adapted to operate in response to an increase of pressure in said discharge means against said valve biasing means and said inlet means pressure whereby an increase in said differential pressure operates said valve to subject said second piston to said discharge pressure and move said stroking means toward said low stroke position.
